M. STUFFLEBEAM

METHOD AND MEANS FOR HANDLING CARS IN MINES

Filed April 19, 1923

UNITED STATES PATENT OFFICE.

MARION STUFFLEBEAM, OF ST. DAVID, ILLINOIS.

METHOD AND MEANS FOR HANDLING CARS IN MINES.

Application filed April 19, 1923. Serial No. 633,302.

To all whom it may concern:

Be it known that I, MARION STUFFLEBEAM, a citizen of the United States, residing at St. David, in the county of Fulton, 5 State of Illinois, have invented certain new and useful Improvements in Methods and Means for Handling Cars in Mines; and I do hereby declare the following to be a full, clear, and exact description of the invention, such as will enable others skilled in the art to which it appertains to make and use the same.

This invention relates to the art of mining, and particularly to the handling of empty and loaded cars in mines, to and from the shaft.

The principal object is to provide a method, and means, whereby to permit the motor car to pull the empty cars from the shaft to the entries, and to pull the loaded cars to the shaft, thus obviating the danger incident to pushing the cars, especially when the train is made up of a large number of cars, and which would prevent the motorman from seeing the track ahead.

Another object is to provide a method and means for accomplishing the result desired, whereby the loaded cars and empty cars are adapted to be placed in such positions that the miners may readily get the empty ones, and the motor car get the loaded ones, without interference.

Other objects and advantages will be apparent from the following description when taken in connection with the accompanying drawing.

In the drawing:

The figure is a diagrammatic view of the trackage used in the method, and the associated portions of the various entries of the mine.

Referring particularly to the accompanying drawing there is shown a sectional detail of a portion of a mine which has the main entry 10, the north entries, and the south entries, there being two north and two south entries shown. The north entries will be designated as 11 and 11', and the south entries as 12 and 12', so that the description, which will follow, will be clear.

Extending longitudinally in the main and side entries, and past the mouths of the north and south entries, are the tracks 13 and 13', the former being termed the side entry track and the latter the main entry

track. At a point on the two tracks 13 and 13', and approximately midway between the mouths of the north entries and south entries, is a switching track 14. Leading from the north entries and connecting with the side entry track, are the north entry tracks 15 and 15', each having a cross over switch, designated by the numerals 16 and 16', which lead over and connect with the main entry track 13'. From the mouths of the south entries tracks 17 and 17' lead and connect with the main entry track, the former being shown at 18 while the latter, as shown at 18', also connect with the side entry track. The mine shaft is designated 60 by the numeral 19. The intersections, or points where the cross overs 18' and 16' cross the main and side entry tracks, there are what are termed "diamonds", designated by the numerals 20 and 20', respectively, the former having the curves 21 and 21' connecting the main entry track 13' with the cross over 18' and the south entry track 17'. Beyond the mouths of the entries 11 and 12 there is disposed a cross over or 65 switching track 22, which connects the side entry track with the main entry track, for a purpose which will presently appear herein. The other diamond 20' has the similar curves 23 and 23', which connect the north 70 entry tracks 15 with the side entry tracks, and the cross over 16 with the side entry 75 tracks.

The filled cars are brought from the north and south entries and placed on the main entry track 13'. The motor car comes from the shaft 19, bringing a train of empty cars, and passes over the curve 21, and the cross over 18', onto the side entry track 13, drawing the cars to a position between the adjacent end of the switching track 14, and the diamond 20'. The motor car is then uncoupled from the empty cars, run along the track 13, and then back, onto the track 13', by means of the switching track 22, and recrosses to the track 13, by means of the track 14. The motor car after being coupled to the other end of the train, pulls the empty cars so that they will not interfere with entrance and exit with respect 80 to the mouths of the entries 11 and 11'. The empty cars will then be in position to be taken to the entries, as needed. The motor car is then uncoupled, runs onto the main entry track 13', over the cross over 18', and 85 90 95 100 105 110

backed up and coupled to the train of loaded cars on the track 13', after which the cars are pulled to the shaft 19.

By this arrangement, the motor car is always at the head of the train of cars, whether the cars are loaded or empty, thus enabling the motorman to see the track ahead, and avoid accidents, incident to the falling of coal from the loaded cars, or striking "side falls" from the "rib of the entry".

What is claimed is:

In a method and means for handling cars in mines, the combination with a mine including longitudinal parallel entries, lateral entries communicating with the parallel entries and being arranged opposite each other

and communicating between the parallel entries, of a railway including tracks extending longitudinally in the parallel entries and past the mouths of the lateral entries, tracks in the lateral entries and having connections with one of the adjacent parallel tracks, communications between the parallel tracks adjacent the lateral entries, and communications between the parallel tracks intermediate the lateral entries.

In testimony whereof, I affix my signature, in the presence of two witnesses:

MARION STUFFLEBEAM.

Witnesses:

FRANK HALE,

FRED. A. WEAVER.
